Solomon Polachek
ATTORNEY

UNITED STATES PATENT OFFICE

NATHAN A. GROSS, OF FORDS, NEW JERSEY, ASSIGNOR TO WILLIAM GROSS, OF FORDS,
NEW JERSEY

DROP SEAT PAJAMA

Application filed September 26, 1931. Serial No. 565,332.

This invention relates to new and useful improvements in pajamas.

The invention has for an object the construction of a pajama which is characterized by a drop seat having end extensions capable of partially extending around to the front of the pajama.

Another object of this invention is the arrangement of strings on the end extensions from the drop seat to allow tying together at the front of the garment.

A still further object of the invention is the provision of shoulder straps in conjunction with the parts previously mentioned.

Furthermore, another one of the objects of this invention is the provision of shoulder straps which extend downward behind the front of the garment and have buttons mounted on their ends which pass through button holes in the front of the garment and provide for connection with the ends of the lateral extensions from the sides of the drop seat.

A still further object of this invention is the construction of a pajama which is of simple, durable construction, dependable in use and efficient in operation and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

35 In the accompanying drawing forming a material part of this disclosure:—

Fig. 1 is a side elevational view of a pajama constructed according to this invention.

40 Fig. 2 is a front elevational view of Fig. 1.
Fig. 3 is a rear elevational view of Fig. 1 but shown with the seat closed.

Fig. 4 is a view similar to Fig. 2 but illustrating a modified construction.

45 Fig. 5 is another view similar to Fig. 2 but illustrates a still further modification.

The pajama, according to this invention, is constructed from material 10 in the form of pajamas. These pajamas are opened at the top or shoulder parts where they are provided with straps 11. The shoulder straps 50 are connected with the rear portion of the pajamas and extend to the front and are engageable therewith by the provision of button and button hole constructions 12. At the back, the pajamas are formed with a seat 55 opening 13 which may be closed by a flap 14. This flap is capable of extending over the top edge of the seat opening as indicated, for example, in Fig. 3. At the sides, the seat flap 14 is formed with extensions 15 which 60 may be brought around to the front of the pajamas and secured thereto by fastening means. As shown in the drawing, buttons 16 located on the front of the garment may pass through button holes 17 formed in the ends 65 of the flaps. The buttons 16 or other fastening means may be moved to any desired position at the front of the garment in order to fit the form of the wearer. In Fig. 1, the dot and dash lines 18 represent the closed position of the seat, which clearly show that no fastening means are needed at the back of the garment.

In Fig. 4 a modification of the invention has been disclosed in which the garment is 75 provided with straps 11^a of exceptional length extending downwards to the front portion of the garment at the front. The free ends of the straps are indicated by reference numerals 19. Buttons 20 or other fastening means engage upon these free ends and pass through button holes 21 formed in the front of the garment. The extensions 15 from the seat of the garment are formed with button holes 17 which may also be engaged over the buttons 20. The garment is 85 unique in the fact that before the shoulder straps may be opened, it is necessary that the seat be opened. This arrangement is of utility in that the seat naturally is left open 90

when the garment is removed from the wearer to expose it for washing.

In Fig. 5 another modification of the invention has been disclosed in which shoulder straps 11^b are used in the form of ribbons so that they may be tied to the front portions of the garment. This eliminates the necessity of buttons. Furthermore, the extensions 15 from the seat portion 14 terminate 5 in ribbons 22 which may be tied together at the front into a bow in closing the seat portion and at the same time shaping the garment to fit the form of the wearer, without using any other fastening means either at 10 the front or back of the said garment.

It is to be understood that my improved drop seat pajama may be provided with any suitable shoulder construction, also that my garment may be made with or without 20 sleeves.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention what I claim as new, and desire to secure by United 30 States Letters Patent is:—

1. In a pajama, material in the form of pajamas open at the shoulders and having shoulder straps attached upon the rear and extendable across to the front for closing the opening, said material being open at the seat portion and provided with an upwardly extended flap for closing this latter mentioned opening, said flap having extensions to the front of the garment, said shoulder straps extending inside and down the front of the garment to the vicinity of the flap extensions, means for detachably securing the upper portion of the front of the garment on to the shoulder straps, and means for detachably securing the free ends of the shoulder straps with the flap extensions, comprising buttons upon the ends of the shoulder straps engageable through button holes formed in the front of the garment and button holes formed in the flap extensions.

2. In a pajama, material in the form of pajamas open at the shoulders and having shoulder straps attached upon the rear and extendable across to the front for closing the opening, said material being open at the seat portion and provided with an upwardly extended flap for closing this latter mentioned opening, said flap having extensions to the front of the garment, said shoulder strap extending inside and down the front of the garment to the vicinity of the flap extensions, means upon the free ends of the shoulder straps and engaging through the upper portion of the front of the garment and for detachably securing the said straps to the garment, and means upon the flap extensions for detachably engaging the means on the strap and extending through the garment so that the straps cannot be detached from the garment without detaching the flap extensions and so that the flap extensions can be detached without detaching the straps.

In testimony whereof I have affixed my signature.
